UNITED STATES PATENT OFFICE.

ROBERT M. ROBINSON, OF LOUISVILLE, KENTUCKY, ASSIGNOR TO CEAETHAM ELECTRIC SWITCHING DEVICE CO. INC., OF LOUISVILLE, KENTUCKY, A CORPORATION OF KENTUCKY.

LOCKING DEVICE FOR ELECTRIC SWITCHES.

Application filed September 28, 1921. Serial No. 503,945.

To all whom it may concern:

Be it known that I, ROBERT M. ROBINSON, a citizen of the United States; and a resident of Louisville, county of Jefferson, and State of Kentucky, have invented a new and useful Improvement in Locking Devices for Electric Switches, of which the following is a specification.

The object of my invention is to provide a locking device for electric switches of the Cheatham type shown in Patent No. 612,702 and subsequent patents, so that it will be impossible to derail a car by having a switch thrown one way by an approaching car and the other way by a following car before the first car is clear of the switch, and a further object is to provide a reliable apparatus which will operate properly without regard to the speed of the cars using the switch. These and other objects are accomplished by my invention, one embodiment of which is hereinafter more particularly set forth.

For a more particular description of my invention, reference is to be had to the accompanying drawings, forming a part hereof, in which—

Figure 1 is a diagrammatic view of a complete system embodying my invention, and

Figure 2 is a side elevation of the locking device.

Through the various views of the drawings, similar reference characters designate similar parts.

In the embodiment of my invention here-
35 in illustrated, a switching system of the Cheatham type is shown in which 1 designates the trolley wire, 2 the conventional trolley pan; or any other trolley pan; 3 the controlling solenoid or relay, 4 and 5 the ground solenoids, 6 the movable core of the ground solenoids and 7 the switch point rail. The trolley pan 2 has a long bar 8 at one side which is connected by a wire 9 to the magnet of the relay 3 and from thence a wire 10 runs to the trolley wire 1. The armature 11 of the relay 3 has a contact plate 12 fixed thereon and this contact plate is connected to a wire 13 which runs to the middle bar 14 on one side of the trolley pan 2. As will appear below, the wire 13 is interrupted between the contacts 15 which are connected together when the device operates in a manner which will be described below. The contact plate 12 normally rests on a fixed con-

tact 16 which is connected to a wire 17 that runs to the solenoid 4 which is grounded through a wire 18. If the magnet be energized sufficiently to raise the core 11, and its connected parts, the plate 12 contacts with an upper fixed contact 19 which is connected by a wire 20 to the magnet 5 of the ground solenoid which solenoid is grounded through a suitable wire 21 in the conventional manner. The core 6 is connected to the switch point rail 7 by means of any suitable mechanism 22 which forms no part of my invention.

Assuming that the contacts 15 and 16 are connected, the operation of the device, as above described, is the ordinary operation 70 of a Cheatham system, that is, assuming a trolley wheel to bridge between the contactors 8 and 14 and to be off the trolley wire 1, the bar 8 is connected to the trolley wire 1 through the wires 9 and 10. If no power 75 be applied to the motors of the car connected to the trolley wheel, the magnet of the relay 3 is not sufficiently energized, if it is energized at all, to raise the core 11 and so a circuit is established through the wire 13, contact 16, ground solenoid 4 and wire 18, so that the switch point 7 is placed for sending the car straight ahead. If power be taken to the motors of the car, then enough electricity passes through the magnet 3 to energize the same sufficiently to raise the core 11 and then the plate 12 contacts with the fixed contact 19 and the ground solenoid 5 is then energized to throw the switch for the curve. At times the apparatus above described will 85 operate where one car follows another too closely so that derailments or other troubles result when the following car is going in the opposite direction from the leading car and the switch point is thrown when the leading car is partially through the switch. To prevent this difficulty, my locking device is employed. This locking device has a wire 23 which has one end connected to a bar 24 on the trolley pan which follows the bar 14 so that the trolley wheel will first connect the bars 8 and 14 and then the bars 8 and 24, as indicated in Figure 1. The bars 14 and 24 are remote enough to have the trolley wheel leave the former before reaching the latter. The wire 23 runs to a resistance 25 and intermediate of the ends of the same so that there is a comparatively low resistance be-

tween the wire 23 and the wire 27. The resistance of the resistance coil 25 may be in the neighborhood of 1400 ohms and the resistance of the magnet 28 may be in the neighborhood of 410 ohms, although this resistance may be varied, if desired. The wire 26 runs to a solenoid 28 which has a wire 29 which connects it to the ground. This solenoid has a core 30 which is insulated on its lower exterior surface, except at the ring 31 which is shown connecting the contacts 15. This ring 31 may connect the lower contacts 15 or the upper contacts 32 depending on whether or not the solenoid 28 is energized. The connections of the contacts 15 have been described above and the contacts 32 connect the wire 27 with a wire 33 that runs to the fixed arm 34 of a trolley wire switch or circuit opener 35.

This trolley wire switch 35 has a base 36 which is fixed on the trolley wire 1 in any desirable manner, and it supports a bar 37 which is fixed thereon and held by screws 38 or by any other suitable means. At its forward end, the bar 37 is provided with a pivot 39 on which is placed a bent contacting device 40 which has its lower end normally resting on the trolley wire 1 and its upper end in contact with the bar 34.

Whenever a trolley wheel raises the lower end of the pivoted contact 40, the upper end is separated from the contact 34 so that the circuit is opened at this point. This contact 34 is insulated from the bar 37 by a suitable insulator 41 so that when the contact 40 is raised, as above described, the fixed contact 34 is not energized.

In view of the foregoing, the operation of my improved locking device will be readily understood. Assuming that a trolley wheel passes through the trolley pan in the direction indicated by the arrow in Figure 1 and the switch point is thrown one way or another, or not thrown according to the exigencies of the situation, this trolley wheel will pass from the bar 14 to the bar 24 and when it connects the bars 24 and 8 the magnet 28 will be energized. In any event, as soon as the magnet 28 is energized the band 31 is drawn away from the contacts 15 and placed in contact with the contacts 32 and then the circuit is opened through the wire 13 so as to prevent any current flowing through either of the ground solenoids 4 or 5 with the result that before the trolley wheel leaves the trolley pan and immediately after it leaves the bar 14 the circuits through the ground solenoids are opened and the switch point rail remains at the place where it belongs. As the trolley wheel proceeds along the trolley wire 1 and before it reaches the releasing device 35 a current will flow through the contact 40 which rests on the trolley wire 1, the fixed contact 34, the wire 33, ring 31, contacts 32, wire 27,

resistance 25, wire 26, solenoid 28 and wire 29 to the ground. As the combined resistance coil 25 and solenoid 28 aggregate something like 1800 ohms the current flow will be small, say one-quarter to one-third of an ampere, the energy used while the trolley wheel is passing from the trolley pan 2 to the circuit opener 35 is very small. As soon as the trolley wheel strikes the movable contact 40 of this circuit opener 35, the circuit is opened and then the current to the solenoid 28 is cut off and immediately thereafter the core 31 falls and opens the circuit through the contacts 32 and closes the circuit through the contacts 15 so that the switching apparatus is ready for another use. The circuit opener 35 is placed with regard to the switch point rail 7 so that a car will be over the switch point rail and free of the same before the trolley wheel of the car acts on the movable contact 40, as above described.

In the preferred embodiment of my invention, the solenoid 28 and the core 30 are so arranged and proportioned that the core is drawn up within a very small fraction of a second after the solenoid 28 is energized and yet the weight of the core 30 is sufficient to make the ring 31 on this core open the circuit between the contacts 32 immediately upon the de-energizing of the solenoid 28 so that a car may pass through the apparatus as fast as a car can pass without danger of derailment under the normal conditions of service and without being delayed in any manner so as to give the apparatus time to act, as above stated.

While I have shown and described one embodiment of my invention, it is obvious that it is not restricted thereto, but that it is broad enough to cover all structures that come within the scope of the annexed claims.

Having thus described my invention, what I claim is:

1. In an apparatus of the class described, an electrically operated switch throwing device with circuits therefor, a solenoid with means connected therewith for opening the switch throwing circuits contained in said switch throwing device and means for closing a circuit through the solenoid for holding open the switch throwing circuits and a circuit opener with a part adapted to be moved by a trolley wheel to open the circuit through said solenoid.

2. In an apparatus of the class described, the combination with an electrically operated switch throwing device, a trolley wire, a trolley pan and a circuit opener with a part adapted to be moved by a trolley wheel, a relay controllable through the trolley pan for transmitting the current from the trolley wire to the switch throwing device, an electric switch opening and closing device made to open and close the circuit through the

relay and connections between said electric switch opening and closing device and said trolley pan and said circuit opening device.

- 5 3. In an apparatus of the class described, a trolley wire with a trolley pan and a circuit opener mounted thereon, a switch throwing device connected to said trolley pan, a circuit opener in circuit with said 10 switching device, a grounded solenoid controlling said circuit opener, connections between said solenoid and the trolley pan and the solenoid and the circuit opener on

the trolley wire and suitable resistances in both of said last mentioned circuits so that when the solenoid is energized the circuit will be opened through the switching device and another circuit closed from the circuit opener on the trolley wire and through the solenoid and resistance, whereby the first circuit will be open through the switching device by a reduced current through the grounded circuit of the solenoid until this circuit is opened through the circuit opener of the trolley wire. 15 20

ROBT. M. ROBINSON.
